Primary Examiner — Thomas Johannes*Assistant Examiner* — Samantha Q Lawrence(74) *Attorney, Agent, or Firm* — R. Reams Goodloe, Jr.(57) **CLAIM**

The ornamental design for a stiffener for orthotic device, as shown and described.

DESCRIPTION

FIG. 1 is a perspective view of a stiffener for orthotic device according to our invention.

FIG. 2 is a front view thereof.

FIG. 3 is a rear view thereof.

FIG. 4 is a left side view thereof.

FIG. 5 is a right side view thereof.

FIG. 6 is a bottom plan view thereof; and,

FIG. 7 is a top plan view thereof.

In the drawing figures, surface shading is used to clearly show the character and contour of surfaces of the 3-dimensional aspects of the design, and form no part of the claimed design.

The characteristic feature of the design resides in a shape for a stiffener for orthotic device.
